UNITED STATES PATENT OFFICE.

HUGH W. SANFORD, OF KNOXVILLE, TENNESSEE.

RAILWAY-CAR BRAKE.

Application filed April 15, 1921. Serial No. 461,562.

To all whom it may concern:

Be it known that I, HUGH W. SANFORD, a citizen of the United States, residing at Knoxville, in the county of Knox and State of Tennessee, have invented a new and useful Improvement in Railway-Car Brakes, of which the following is a specification, reference being had to the accompanying drawing.

10 My improvement relates particularly to brakes for mine cars and similar small cars.

The object of the invention is to simplify and reduce cost and at the same time produce an effective brake.

15 In the accompanying drawings,

Fig. 1 is a side elevation of a part of a mine car embodying my improvement;

Fig. 2 is an end elevation of the same car;

20 Fig. 3 is a section on the line, 3—3, of Fig. 2, looking toward the right;

Fig. 4 is a side elevation of a car embodying my invention in another form;

25 Fig. 5 is an upright section on the line, 5—5, of Fig. 4, looking in the direction of the arrow;

Fig. 6 is a detail view showing some parts of the mechanism separated from each other.

Referring first to Figs. 1, 2 and 3 of the drawings, A is the car body, and B, B are 30 the car wheels. C, C are two brake straps, one of which is applied to each of two wheels, B, at the same side of the car.

35 Between the wheels and above the level of the axles are two bracket bearings, D, D, which are secured to the body of the car and receives the horizontal rock shaft, E, which also rests in a third bracket bearing, D¹, located on the side of the car body, near the right hand end of the car as shown 40 in Fig. 1. Between the bearings, D, D, the shaft, E, is bent laterally to form a crank, E¹, extending outward away from the car a short distance. Two hangers, F, F, are supported by the crank, E¹, and extend 45 downward, and each has its lower end, F¹, bent toward the adjacent wheel. A horizontal bridge bar, F², extends from one hanger, F, to the other and has oblique ends, F³, bearing against the oblique ends, F¹, of the hangers. A bolt, F⁴, extends through 50 each end of the bridge plate and the adjacent hanger and the adjacent upturned end, C¹, of the adjacent brake strap, C. Nuts, F⁵, are placed on said bolt to bind the hangers 55 and the bridge plate to each other and to bind the brake strap against the head of

the bolt. The opposite end of the brake strap is secured to a bracket, C², secured to the side of the car body in position to bring that end of the brake strap lower than the 60 upper part of the adjacent wheel.

The nuts, F⁵, which are located at opposite sides of the ends, F¹ and F², of the hangers, F, and bridge bar, F², permit making separate adjustment between each brake 65 strap and the crank. If said nuts on either bolt are moved toward the head of that bolt, the contact between the adjacent strap and the adjacent wheel will be made sooner. By means of this adjustment, the parts may be 70 so arranged as to cause simultaneous engagement between the straps and the wheels.

From the bracket bearing, D¹, the rock shaft, E, extends horizontally toward the 75 right beyond the end of the car body. There it is bent horizontally across the end of the car body and parallel to the latter to form a long arm, E². Near its end, said arm is flattened to form a blade, E³, having a lower 80 outward-directed edge, E⁴. An approximately upright rack bar, E⁵, having teeth, E⁶, extends across the arm, E², and is secured to the end of the car body by bolts, E⁷. The edge, E⁴, of the blade, E³, is adapted to engage the teeth, E⁶, and prevent downward movement of the arm, E².

The crank, E¹, and the arm, E², are at opposite sides of the axial line of the shaft, E. Hence when the arm, E², is raised, the 90 crank, E¹, is moved downward, whereby the hangers, F, the bridge bar, F², the bolts, F⁴, and the adjacent ends of the brake straps are forced downward, whereby the brake straps are put under tension and made to bear 95 actively upon the wheels, B, B. When the brakes are to be set, the arm, E², is raised manually and drawn against the teeth, E⁶, of the rack bar, E⁵, so as to make engagement between the edge, E⁴, and one of said teeth 100 when the arm reaches its upper limit. Thus the arm will be locked, and thereby the engagement of the brake straps is maintained. This engagement is intensified through the flexibility of the shaft, E, and the arm, E², 105 the shaft and said arm being together of sufficient length to allow appreciable flexing, although a short section of the shaft or arm would be practically inflexible.

While provision is thus made for effectively applying the brake straps and holding them when applied, provision is also

made for automatically holding the brake straps out of engagement when application is not desired. This is accomplished by placing the weight of the relatively long 5 arm, E^2 , in opposition to the crank, E^1 , and the parts supported by said crank. When the arm, E^2 , has been released from the teeth of the rack bar, E^5 , said arm, by the action of gravity assumes its lowest position and by its downward movement lifts 10 the relatively short crank, E^1 , and all the parts supported thereby, whereby the brake straps are held out of action. The arm, E^2 , as shown, extends across the end of the car, 15 and, as above indicated, such length gives the arm the weight needed to adapt the arm to tend to turn the rock shaft for the release of the brake mechanism. Furthermore, thus lengthening the arm makes it accessible by 20 an attendant from either side of the car.

It is now to be observed that a minimum amount of mechanism and simple movements are involved in the effective application of the brakes. To apply brake mechanism to 25 two wheels, one being located at one side and the other at the other side of the car, as has heretofore been done, requires mechanism that is more complex and more expensive to construct. In this connection, it is to be ob- 30 served that in cars of this class, the body of the car usually extends downward close to the track and precludes use of the type of brake construction used in larger railway cars having bodies high above the tracks.

35 In the form shown in Figs. 4, 5 and 6, the rock shaft, E , rests in only two bearings, D and D^1 , and the crank is a single arm, E^8 , to which is coupled the upper end of a stem, G , which extends slidably through a bracket, G^1 , and through the single brake strap, H , extending from one bracket, C^2 , to the other bracket, C^2 , and said strap extending downward between the two wheels. The stem, G , also extends through a washer plate, G^2 , resting on the strap and making wider engagement with the strap than would be made if the nut, G^3 bore upon the strap. A nut, G^3 , surrounds said stem above said plate and below the strap two nuts, G^4 , surround 50 said stem. By raising or lowering the nuts, G^3 and G^4 , on the stem, G , the strap, H , is adjusted relative to said stem, for bringing the arm, E^8 , to the desired angle when the straps engage the wheels. The opening in 55 the bracket, G^1 , through which the stem, G , extends is larger than the thickness of said stem in the direction parallel to the length of the car, in order that the lower part of the stem, G , may swing parallel to the length 60 of the car for equalizing engagement of the strap on the wheels. (Fig. 4).

65 The operation of this form of the mechanism is similar to the operation of the mechanism shown by Figs. 1, 2 and 3. When the arm, E^2 , is raised, the stem, G , is forced

downward, whereby the strap H , is applied to the two wheels. When the arm, E^2 , is free, the stem, G , is lifted by the weight of the arm, E^2 , whereby the strap, H , is lifted.

It is now to be observed that both forms 70 of the structure may be produced with a limited amount of labor. No castings are needed in either form. In the first form no forging is needed excepting to form the rack bar and the blade, E^3 , on the arm, E^2 . 75 The rest of the work is merely cutting and punching and bending. The bolts, F^4 , are ordinary bolts threaded to the head. The nuts are ordinary stock nuts. The brackets, C^2 , D and D^1 are formed of ordinary stock 80 metal. In the form of Figs. 4, 5 and 6, the arm, E^8 , and the stem, G , are produced by simple forging. It is also to be observed that the application of the various parts to the car is easily accomplished.

85 I claim as my invention,

1. The combination with the car body and a wheel at one side of the car, of a horizontal rock shaft arranged parallel to and supported at one side of the car body and having a crank, brake means jointed to said crank and adapted to be pressed downward into engagement with said wheel when said rock shaft is turned to move said crank downward, and rigid means extending approximately horizontally across the end of the car and normally acting on said shaft to turn said shaft to lift said crank and said brake means and said turning means being adapted to be moved manually to turn said shaft in the opposite direction, substantially as described.

2. The combination with the car body and a wheel at one side of the car, of a horizontal rock shaft arranged parallel to and supported at one side of the car body and having a crank, means, including a brake strap, jointed to said crank and adapted to press said strap into engagement with said wheel when said rock shaft is turned to move said crank downward, and rigid means extending approximately horizontally across the end of the car and normally acting to turn said shaft to lift said crank and said brake means and said turning means being adapted to be moved manually to turn said shaft in the opposite direction, substantially as described.

3. The combination with the car body and a wheel at one side of the car, of a horizontal rock shaft arranged parallel to and supported at one side of the car body and having a crank, brake means engaged by said crank and adapted to be pressed into engagement with said wheel when said rock shaft is turned to move said crank downward, an arm on said shaft at the side of the latter opposite the crank and extending approximately horizontally across the end of the car, whereby the weight of said arm

will lift said crank and the brake means when said arm is free and whereby said arm is made accessible from both sides of the car, and means for engaging and holding 5 said arm when said shaft has been turned to make said engagement, substantially as described.

4. The combination with the car body and a wheel at one side of the car, of a horizontal rock shaft arranged parallel to and supported at one side of the car body and having a crank, means, including a brake-strap, engaged by said crank and adapted to be pressed into engagement with said wheel 10 when said rock shaft is turned to move said crank downward, an arm on said shaft at the side of the latter opposite the crank and extending approximately horizontally across the end of the car, whereby the weight of 15 said arm will lift said crank and the brake means when said arm is free and whereby said arm is made accessible from both sides of the car, and means for engaging and holding said arm when said shaft has been 20 turned to make said engagement, substantially as described.

5. The combination with a car body and two wheels at one side of the car, of a horizontal rock shaft arranged parallel to and supported at one side of the car body and having a crank, brake means engaged by 25 said crank and adapted to be pressed into engagement with said two wheels when said rock shaft is turned to move said crank downward, a long arm rigid on the rock shaft and extending approximately horizontally across the end of the car, and means for engaging and holding said arm when 30 said arm has been raised and the shaft so turned, substantially as described.

6. The combination with a car body and two wheels at one side of the car, of a horizontal rock shaft arranged parallel to and supported at one side of the car body and having a crank, and brake strap means engaged by 35 said crank and adapted to be pressed into engagement with said two wheels when said rock shaft is turned to move said crank downward, a long arm rigid on the rock shaft and extending approximately horizontally across the end of the car, and means for engaging and holding said arm when said arm has been raised and the shaft so turned, substantially as described.

7. The combination with a car body and two wheels at one side of the car, of a horizontal rock shaft arranged parallel to and supported at one side of the car body and having a crank, brake means engaged by 40 said crank and adapted to be pressed into engagement with said two wheels when said rock shaft is turned to move said crank downward, an arm on said shaft at the side opposite the crank and extending approxi-

mately horizontally across the end of the car, whereby the weight of said arm will lift said crank and the brake means when said arm is free and whereby said arm is made accessible from both sides of the car, 70 and means for engaging and holding said arm when said shaft has been turned to make said engagement, substantially as described.

8. The combination with a car body and two wheels at one side of the car, of a horizontal rock shaft arranged parallel to and supported at one side of the car body and having a crank, brake strap means engaged by 75 said crank and adapted to be pressed into engagement with said two wheels when said rock shaft is turned to move said crank downward, an arm on said shaft at the side opposite the crank and extending approximately horizontally across the end of the 80 car, whereby the weight of said arm will lift said crank and the brake means when said arm is free and whereby said arm is made accessible from both sides of the car, and means for engaging and holding said 85 arm when said shaft has been turned to make said engagement, substantially as described.

9. The combination with the car body and a wheel at one side of the car, of a horizontal rock shaft arranged parallel to and supported at one side of the car body and having a crank, brake means engaged by 90 said crank and adapted to be pressed into engagement with said wheel when said rock shaft is turned to move said crank downward, a long arm rigid on the rock shaft and extending approximately horizontally across the end of the car, an upright rack 95 bar for engaging and holding said arm 100 when said arm has been raised and the shaft so turned, substantially as described.

10. The combination with the car body and a wheel at one side of the car, of a horizontal rock shaft arranged parallel to and supported at one side of the car body and having a crank, means, including a brake strap, engaged by 105 said crank and adapted to press said strap into engagement with said wheel when said rock shaft is turned to move said crank downward, a long arm rigid on the rock shaft and extending approximately horizontally across the end of the car, an upright rack bar for engaging 110 and holding said arm when said arm has been raised and the shaft so turned, substantially as described.

11. The combination with the car body and a wheel at one side of the car, of a horizontal rock shaft arranged parallel to and supported at one side of the car body and having a crank, brake means engaged by 115 said crank and adapted to be pressed into engagement with said wheel when said rock shaft is turned to move said crank 120

downward, an arm on said shaft at the side of the latter opposite the crank and extending approximately horizontally across the end of the car, whereby the weight of said 5 arm will lift said crank and the brake means when said arm is free and whereby said arm is made accessible from both sides of the car, and a rack bar for engaging and holding said arm when said shaft has been 10 turned to make said engagement, substantially as described.

12. The combination with the car body and a wheel at one side of the car, of a horizontal rock shaft arranged parallel to and 15 supported at one side of the car body and having a crank, means, including a brake-strap, engaged by said crank and adapted to be pressed into engagement with said wheel when said rock shaft is turned to 20 move said crank downward, an arm on said shaft at the side of the latter opposite the crank and extending approximately horizontally across the end of the car, whereby the weight of said arm will lift said crank 25 and the brake means when said arm is free and whereby said arm is made accessible from both sides of the car, and a rack bar for engaging and holding said arm when said shaft has been turned to make said 30 engagement, substantially as described.

13. The combination with a car body and two wheels at one side of the car, of a horizontal rock shaft arranged parallel to and supported at one side of the car body and 35 having a crank, brake means engaged by said crank and adapted to be pressed into engagement with said two wheels when said rock shaft is turned to move said crank downward, a long arm rigid on the rock 40 shaft and extending approximately horizontally across the end of the car, an upright rack bar for engaging and holding said arm when said arm has been raised and said shaft so turned, substantially as 45 described.

14. The combination with a car body and two wheels at one side of the car, of a horizontal rock shaft arranged parallel to and supported at one side of the car body and 50 having a crank, and brake strap means engaged by said crank and adapted to be pressed into engagement with said two wheels when said rock shaft is turned to move said crank downward, a long arm rigid 55 on the rock shaft and extending approximately horizontally across the end of the car, an upright rack bar for engaging and holding said arm when said arm has been raised and said shaft so turned, substantially 60 as described.

15. The combination with a car body and two wheels at one side of the car, of a horizontal rock shaft arranged parallel to and supported at one side of the car body and 65 having a crank, brake means engaged by

said crank and adapted to be pressed into engagement with said two wheels when said rock shaft is turned to move said crank downward, an arm on said shaft at the side opposite the crank and extending approximately horizontally across the end of the car, whereby the weight of said arm will lift said crank and the brake means when said arm is free and whereby said arm is made accessible from both sides of the car, and a rack bar 70 for engaging and holding said arm when said shaft has been turned to make engagement, substantially as described.

16. The combination with a car body and two wheels at one side of the car, of a horizontal rock shaft arranged parallel to and supported at one side of the car body and having a crank, brake strap means engaged by said crank and adapted to be pressed into engagement with said two wheels when said rock shaft is turned to move said crank downward, an arm on said shaft at the side opposite the crank and extending approximately horizontally across the end of the car, whereby the weight of said arm will lift 80 said crank and the brake means when said arm is free and whereby said arm is made accessible from both sides of the car, and a rack bar for engaging and holding said arm when said shaft has been turned to make engagement, substantially as described.

17. The combination with the car body and a wheel at one side of the car, of a horizontal rock shaft arranged parallel to and supported at one side of the car body and having a crank, brake means, including a hanger, engaged by said crank and adapted to be pressed into engagement with said wheel when said rock shaft is turned to move said crank downward, a long arm rigid 100 on the rock shaft and extending approximately horizontally across the ends of the car, and means for engaging and holding said arm when said arm has been raised and the shaft so turned, substantially as 105 described.

18. The combination with the car body and a wheel at one side of the car, of a horizontal rock shaft arranged parallel to and supported at one side of the car body and having a crank, means, including a brake strap, and a hanger, engaged by said crank and adapted to press said strap into engagement with said wheel when said rock shaft is turned to move said crank downward, a long arm rigid on the rock shaft and extending approximately horizontally across the end of the car, and means for engaging and holding said arm when said arm has been raised and the shaft so turned, substantially 115 as described.

19. The combination with the car body and a wheel at one side of the car, of a horizontal rock shaft arranged parallel to and supported at one side of the car body and 120

- having a crank, brake means, including a hanger, engaged by said crank and adapted to be pressed into engagement with said wheel when said rock shaft is turned to move said crank downward, an arm on said shaft at the side of the latter opposite the crank and extending approximately horizontally across the end of the car, whereby the weight of said arm will lift said crank and the brake means when said arm is free and whereby said arm is made accessible from both sides of the car, and means for engaging and holding said arm when said shaft has been turned to make said engagement, substantially as described.
20. The combination with the car body and a wheel at one side of the car, of a horizontal rock shaft arranged parallel to and supported at one side of the car body and having a crank, means, including a brake-strap and a hanger engaged by said crank and adapted to be pressed into engagement with said wheel when said rock shaft is turned to move said crank downward, an arm on said shaft at the side of the latter opposite the crank and extending approximately horizontally across the end of the car, whereby the weight of said arm will lift said crank and the brake means when said arm is free and whereby said arm is made accessible from both sides of the car, and means for engaging and holding said arm when said shaft has been turned to make said engagement, substantially as described.
25. The combination with a car body and two wheels at one side of the car, of a horizontal rock shaft arranged parallel to and supported at one side of the car body and having a crank, brake means when said arm is free and whereby said arm is made accessible from both sides of the car, and means for engaging and holding said arm when said shaft has been turned to make said engagement, substantially as described.
30. 21. The combination with a car body and two wheels at one side of the car, of a horizontal rock shaft arranged parallel to and supported at one side of the car body and having a crank, brake means, including a hanger, engaged by said crank and adapted to be pressed into engagement with said two wheels when said rock shaft is turned to move said crank downward, a long arm rigid on the rock shaft and extending approximately horizontally across the end of the car, and means for engaging and holding said arm when said arm has been raised and the shaft so turned, substantially as described.
35. 22. The combination with a car body and two wheels at one side of the car, of a horizontal rock shaft arranged parallel to and supported at one side of the car body and having a crank, and brake strap means, including a hanger, engaged by said crank and adapted to be pressed into engagement with said two wheels when said rock shaft is turned to move said crank downward, a long arm rigid on the rock shaft and extending approximately horizontally across the end of the car, and means for engaging and holding said arm when said arm has been raised and the shaft so turned, substantially as described.
40. 23. The combination with a car body and two wheels at one side of the car, of a horizontal rock shaft arranged parallel to and supported at one side of the car body and having a crank, brake means, including two brake straps, engaged by said crank and adapted to be pressed into engagement with said two wheels when said rock shaft is turned to move said crank downward, a long arm rigid on the rock shaft and extending approximately horizontally across the end of the car, and means for engaging and holding said arm when said arm has been lifted and the shaft so turned, substantially as described.
45. 24. The combination with a car body and two wheels at one side of the car, of a horizontal rock shaft arranged parallel to and supported at one side of the car body and having a crank, brake strap means, including a hanger, engaged by said crank and adapted to be pressed into engagement with said two wheels when said rock shaft is turned to move said crank downward, an arm on said shaft at the side opposite the crank and extending approximately horizontally across the end of the car, whereby the weight of said arm will lift said crank and the brake means when said arm is free and whereby said arm is made accessible from both sides of the car, and means for engaging and holding said arm when said shaft has been turned to make said engagement, substantially as described.
50. 25. The combination with a car body and two wheels at one side of the car, of a horizontal rock shaft arranged parallel to and supported at one side of the car body and having a crank, brake means, including two brake straps, engaged by said crank and adapted to be pressed into engagement with said two wheels when said rock shaft is turned to move said crank downward, a long arm rigid on the rock shaft and extending approximately horizontally across the end of the car, and means for engaging and holding said arm when said arm has been lifted and the shaft so turned, substantially as described.
55. 26. The combination with a car body and two wheels at one side of the car, of a horizontal rock shaft arranged parallel to and supported at one side of the car body and having a crank, brake means, including two brake straps, engaged by said crank and adapted to be pressed into engagement with said two wheels when said rock shaft is turned to move said crank downward, a relatively long arm on said shaft at the side opposite the crank and extending approximately horizontally across the end of the car, whereby the weight of said arm will lift

said crank and the brake means when said arm is free and whereby said arm is made accessible from both sides of the car, and means for engaging and holding said arm when said shaft has been turned to make said engagement, substantially as described.

27. The combination with a car body and two wheels at one side of the car, of a horizontal rock shaft arranged parallel to and supported at one side of the car body and having a crank, brake means, including two brake straps, engaged by said crank and adapted to be pressed into engagement with said two wheels when said rock shaft is turned to move said crank downward, a relatively long arm on said shaft at the side opposite the crank, and extending approximately horizontally across the end of the car, whereby the weight of said arm will lift said crank and the brake means when said arm is free and whereby said arm is made accessible from both sides of the car, and a rack bar engaging and holding said arm when said shaft has been turned to make said engagement, substantially as described.

28. The combination with a car body and two wheels at one side of the car, of a horizontal rock shaft arranged parallel to and supported at one side of the car body and having a crank elongated parallel to the shaft axis, brake means, including a pair of hangers, engaged by said crank and adapted to be pressed into engagement with said two wheels when said rock shaft is turned to move said crank downward, an arm on said shaft at the side opposite the crank, whereby the weight of said arm will lift said crank and the brake means when said arm is free, and means for engaging and holding said arm when said shaft has been

turned to make said engagement, substantially as described.

29. The combination with a car body and two wheels at one side of the car, of a horizontal rock shaft arranged parallel to and supported at one side of the car body and having a crank, two brake straps, two hangers on the crank, one being attached to one and the other to the other of said straps, whereby said straps are adapted to be pressed into engagement with said two wheels when said rock shaft is turned to move said crank downward, and means for engaging and holding said rock shaft when said shaft has been so turned, substantially as described.

30. The combination with a car body and two wheels at one side of the car, of a horizontal rock shaft arranged parallel to and supported at one side of the car body and having a crank, two brake straps, hangers joined to said straps, and a bridge bar separating the hangers, whereby the straps are adapted to be pressed into engagement with said two wheels when said rock shaft is turned to move said crank downward, and means for engaging and holding said rock shaft when said shaft has been so turned, substantially as described.

31. In a railway car, a plurality of wheels at one side of the car, a strap brake for each of said wheels, a hanger for each strap brake and a common mechanism in operative relation with each of said hangers for by downward pressure simultaneously actuating said hangers and brakes, substantially as described.

In testimony whereof I have signed my name, this 13th day of April, in the year one thousand nine hundred and twenty-one.

HUGH W. SANFORD.
